UNITED STATES PATENT OFFICE.

GUSTAV VON HÜTSCHLER, OF HINDENBURG, GERMANY.

THERAPEUTIC APPLIANCE.

Application filed June 9, 1927. Serial No. 197,583.

This invention relates to a therapeutic light-radiating appliance of the kind provided with means for producing electric induction currents which may either be passed directly through the human body or be employed for inducing currents in the same.

The invention consists in the combination with a metal cage wherein an electric lamp and an induction coil are enclosed and wherein the primary of said coil is in series with the lamp, of means whereby the secondary of the coil can either be short-circuited through the cage or arranged, by the insertion of a terminal plug, in circuit with other elements.

Fig. 1 of the accompanying drawings represents a longitudinal section of the apparatus,

Fig. 2, a view of a detachable electrode, and

Fig. 3, a sectional view of the upper part of the apparatus showing the position of the elements when the electrode of Fig. 2 is attached.

The apparatus has a base composed of a casing 1 which supports an induction coil 2 and which is connected by bars 11 to a ring 11^a so as to form a cage. Within this cage an electric lamp 9 is located. The lamp is mounted in a holder 8 which is supported on the coil 2 by means of a metal plate 7. A shouldered insulating disc 12 arranged within and supported on the ring 11^a, holds a metal plate 21 between which and the plate 7 a semi-cylindrical metal reflector 22 for the lamp is supported so as to be in electric connection with the two plates. The edges of the plates are raised for the retention between the plates of a cylinder 23 of plain or coloured glass.

The insulating disc 12, which is held in position on the ring 11^a by means of a screw cap 14, supports a screw socket 18 for the reception of a screw 19 having an insulated head or knob 19. About the socket 18 a sleeve 15 is arranged which is slidably guided in the insulating disc 12 and which projects beyond the top surface of the latter. A spring 17 supported on the plate 21, bears against a flange 16 on the sleeve 15 and tends to hold said flange against a plate 13 carried by the insulating disc 12. The head of the screw 19 is recessed at 19^a so that it can be screwed over the socket 18 into close contact with the sleeve 15 but without normally de-

pressing the same. However, when a lug or like terminal 20 (Fig. 20) is inserted between the head of the screw 19 and the end of the sleeve 15 and the screw is tightened up, the sleeve will be depressed so as to interrupt the contact between the flange 16 and the plate 13. The latter is connected through the ring 16 and through the bars 11 with the casing 1, and the casing is connected at 24 with one pole of the secondary 2^b of the induction coil 2. The other pole of the secondary is connected to the plate 7. The primary 2^a of the induction coil is arranged in series with the lamp 9 and receives its current from a lead 10.

The induction coil has an iron core 3 whereby its efficiency can be regulated in known manner. The adjustment of the core is effected by means of a screw 4, and an index 5 is provided whereby any particular setting can be repeated by reference to a scale 6.

Normally the apparatus is used for light-treatment and the light may be modified by surrounding the lamp with differently coloured glass cylinders 23. The lamp is fed with alternating current which, as it passes through the primary of the induction coil, induces a high voltage current in the secondary of the coil. Normally the latter is short-circuited through the cage owing to the contact of the flange 16 with the plate 13. The current passing through the cage sets up around the latter an electric field which can be utilized for therapeutic purposes. If it is desired to pass the high voltage currents through the body, the terminal 20, which is connected by a lead to an electrode 25, is inserted under the screw 19 and clamped in position. The sleeve 15 is then depressed, and the contact between the flange 16 and the plate 13 is interrupted. If now the electrode 25 is placed on one part of the body and the casing 1 on another part, the circuit of the secondary coil will be closed through the plate 7, the reflector 22, the plate 21, the spring 17, the sleeve 15, the terminal 20, the electrode 25, and through the body to which the electrode and the casing 1 have been applied.

The current may be passed in this manner through a bar for which purpose a second electrode and lead, like Fig. 2, may be connected to a terminal screw 26 on the casing 1.

The cage may be completed by means of rings 11^b connected to the bars 11.

The lamp 9, instead of being arranged in series with the induction coil, may be arranged in a shunt circuit.

I claim:

- 5 1. A therapeutic appliance comprising a metal cage, an electric lamp and an induction coil enclosed in said cage, and a screw clamp mounted on the cage, the primary of said coil being fed from the same source
- 10 as the lamp, the secondary of the coil being normally connected through said screw clamp with opposite ends of the cage, the screw clamp being adapted to receive a terminal plug and to be disconnected itself
- 15 electrically from the cage when said plug is applied, whereby a terminal connected with the plug may be employed in connection with the cage as a second terminal for closing the circuit of the secondary when said
- 20 terminals are applied to an interposed conducting body.
2. The structure claimed in claim 1 in combination with an insulating disc to which the screw clamp is connected, and a
- 25 screw cap for retaining said insulating disc on the cage.
3. The structure claimed in claim 1 in combination with a semi-cylindrical metal reflector for the lamp, said reflector being
- 30 arranged in the circuit of the secondary between the latter and the screw clamp.

4. A therapeutic appliance comprising a metal cage, an electric lamp, an inductance coil, said lamp and coil being enclosed in said cage, the primary of said coil being conductively connected with the lamp and the secondary of the coil being normally short-circuited through the cage, and an adjustable make and break contact for controlling the circuit of the secondary, said contact being operative for opening the circuit of the secondary and connecting an auxiliary conductor therewith, said conductor being operative as a terminal in conjunction with the cage as a second terminal for closing the circuit of the secondary when said terminals are applied to an interposed conducting body.

5. A therapeutic appliance according to claim 1 wherein a screw clamp is arranged with a spring influenced contact sleeve in the circuit of the secondary and is adapted by adjustment of said sleeve to normally effect the short circuiting of the same through the cage and wherein the insertion of a terminal plug in the clamp causes the sleeve to be electrically disconnected from the cage, substantially as set forth.

GUSTAV VON HÜTSCHLER.
